UNITED STATES PATENT OFFICE.

GISABURO F. SAITO, OF NEW YORK, N. Y.

DESIGN FOR A FERN OR FLOWER DISH.

60,175.

Specification for Design.

Patented Jan. 3, 1922.

Application filed November 13, 1920. Serial No. 423,997. Term of patent 14 years.

To all whom it may concern:

Be it known that I, GISABURO F. SAITO, a subject of Japan, residing at New York, in the county of New York and State of New York, have invented a new, original, and ornamental Design for a Fern or Flower Dish, of which the following is a specification, reference being had to the accompanying drawing, forming part thereof.

In the drawings:—

Figure 1, is a side elevational view of the fern or flower dish, and

Figure 2, is a top plan view of the same.

I claim:—

The ornamental design for a fern or flower dish, as shown.

GISABURO F. SAITO.
